COMBINATION BOOKLET TAG

Edward C. Marshall, Upper Montclair, and Robert W. Swett, Butler, N.J., assignors to American Tag Company, Chicago, Ill., a corporation of Illinois
Filed Feb. 5, 1958, Ser. No. 713,323
10 Claims. (Cl. 40—2)

The principal object of this invention is to provide a combination booklet tag wherein the tag has a tag portion and a detachable coupon portion at one end of the tag portion, wherein a fastening wire is secured at the other end of the tag portion so that the tag portion may be fastened thereby to a suitable object, wherein a booklet overlies the tag and is arranged within the confines of the tag, wherein the booklet is secured to the coupon portion of the tag so that it is removed from the tag when the coupon portion of the tag is detached from the tag portion of the tag, and wherein the fastening wire is removably anchored in place along the tag and maintained within the confines of the tag to prevent dislocation of the fastening wire during handling of the combination booklet tag.

The combination booklet tags of this invention have particular utility when used as guarantee tags, where the guarantee tag portions are fastened to the object being guaranteed and where the coupon portion and informative booklet secured thereto are retained by the purchaser. They also have particular utility where they are to be handled by automatic machinery, as for example, where they are automatically supplied in strip form, such as from rolls of combination booklet tags, to packaging machinery where it is desired to include tags with articles being packaged. Because the booklets and fastening wires of the combination booklet tags of this invention are firmly secured and anchored in place they may be readily handled in strip form in automatic machinery, and also individually, without dislocation of the booklets and fastening wires.

Further objects of the invention are directed to the details of construction of the combination booklet tags and to the cooperative relationship between the component parts thereof.

Other objects and advantages of this invention will become apparent to those skilled in the art upon reference to the accompanying specifications, claims and drawings in which:

FIG. 1 is a perspective view of several rolls of combination booklet tags of this invention arranged in a stack;

FIG. 2 is an enlarged view of a portion of a strip of combination booklet tags corresponding to one form of the invention;

FIG. 3 is a perspective view of a combination booklet tag illustrated in FIG. 2 and showing one face thereof;

FIG. 4 is a view similar to FIG. 3 but showing the other face of the combination booklet tag;

FIG. 5 is a vertical sectional view taken substantially along the line 5—5 of FIG. 3;

FIG. 6 is a perspective view similar to FIG. 3 but illustrating the booklet bent away from the tag;

FIG. 7 is a perspective view similar to FIG. 3 but illustrating still another form of the invention;

FIG. 8 is a vertical sectional view taken substantially along the line 8—8 of FIG. 7; and

FIG. 9 is a view similar to FIG. 7 but illustrating the booklet thereof folded away from the tag.

In FIG. 1 a plurality of rolls of combination booklet tags are shown stacked one upon the other as generally indicated at 10. Each roll 11 of the combination booklet tags is supported by a disc 12 so that the rolls of tags may be conveniently stacked one on top of the other.

2

The roll 11 is formed from a continuous strip of combination booklet tags 13, the tags 13 being arranged side by side in the strip.

As shown more clearly in FIGS. 2 to 6, each tag 13 includes a tag portion 14 and a detachable coupon portion 15 at one end of the tag portion 14. The two portions 14 and 15 of the tag are detachably secured together by a line 16 of perforations so that the coupon portion 15 may be readily detached from the tag portion 14. The tags 13, which are arranged side by side in the strip, have their side edges interconnected as indicated at 17. Thus the various tags may be separated readily from the strip by tearing the connections 17.

Each combination booklet tag 13 is provided at one end with a hole 19 reinforced by patches 20 adhesively secured to the tag. A fastening wire 21 is extended through the hole 19 and is twisted together as indicated at 22 for securing the fastening wire in the hole 19 at the end of the tag opposite from the line 16 of perforations. The wire 21 extends along one face of the tag 13 toward the coupon portion 15 thereof. The tag 13 is provided with an opening 23 in the form of a hole or slit and the wire 21 extends therethrough. Preferably the wire 21 is bent backwardly upon itself with the bent back portions also extending through the hole or slit 23. By so doing, the wire 21 is maintained within the confines of the tag 13 even though the wire, when extended, should be longer than the tag 13. Since the wire 21 extends through the opening 23 it is firmly removably anchored in place along the tag 13 so that dislocation thereof during handling of the tag is prevented.

A booklet 25 overlies the coupon portion 15 of the tag and at least a part of the tag portion 14 of the tag, the booklet 25 being arranged within the confines of the tag 13. The booklet 25 is secured to the coupon portion 15 of the tag in any desired manner as for example, by a staple 26. Preferably the booklet 25 lies along the face of the tag 13 which is opposite from the face along which the fastening wire 21 extends. This provides free access to the fastening wire 21. The tag portion 14 of the tag is preferably provided with slits 27 adjacent the reinforced hole 19 to form a pair of tabs 27. The free end of the booklet 25 is received under the tabs 27 for the purpose of removably anchoring the free end of the booklet in place on the tag portion 14.

Another form of the combination booklet tag of this invention is illustrated in FIGS. 7, 8 and 9 and here also the same tag 13 having the tag portion 14 and the coupon portion 15 and the same booklet 25 are utilized. Like reference characters have been utilized for like parts. In this form of the invention the booklet 25 is folded over and is secured, as by a staple 32, to the coupon portion 15 of the tag. The coupon portion 15 is then folded along the line of perforations 16 so as to overlie a portion of the tag portion 14. In the folded position the booklet 25 is preferably arranged between the tag portion 14 and the coupon portion 15. The tag 13 is provided with a hole 33 at the line 16 of perforations and when the coupon portion 15 is folded against the tag portion 14 the hole 33 forms a notch as illustrated in FIGS. 7 and 8. The fastening wire 21 extends along one face of the tag 13, extends through the notch 33 and is bent back along the other face of the tag. In this way the fastening wire 21 is removably anchored in place along the tag. Preferably the fastening wire 21 extends over the booklet 25 and the coupon portion 15 as it extends toward the notch 33. Thus the fastening wire 21 operates to hold the coupon portion 15 in place when it is folded and to removably anchor the booklet 25.

In both forms of the invention the booklet 25 is secured to the coupon portion 15 of the tag and the same are readily detachable from the tag portion 14 of the

tag. The tag portion 14 of the tag may be readily fastened by the fastening wire 21 to any desired object. The booklet 25 is securely removably anchored in place on the tag 13 and within the confines thereof and the fastening wire 21 is also removably anchored in place along the tag so as to prevent dislocation thereof during handling of the combination booklet tag.

While for purposes of illustration, two forms of this invention have been disclosed, other forms thereof may become apparent to those skilled in the art upon reference to this disclosure and, therefore, this invention is to be limited only by the scope of the appended claims.

We claim as our invention:

1. A combination booklet tag comprising a tag having a tag portion and a detachable coupon portion at one end of the tag portion, a fastening wire secured at the other end of the tag portion of the tag and extending along the tag toward the coupon portion thereof, a booklet overlying the coupon portion of the tag and at least a part of the tag portion of the tag, and means for removably anchoring the fastening wire in place along the tag and for securing the booklet to the coupon portion of the tag.

2. A combination booklet tag comprising a tag having a tag portion and a detachable coupon portion at one end of the tag portion, a fastening wire secured at the other end of the tag portion of the tag and extending along one face of the tag toward the coupon portion thereof, a booklet overlying the coupon portion of the tag and at least a part of said one face of the tag portion of the tag and arranged beneath the fastening wire, and means for removably anchoring the fastening wire in place along the tag and for securing the booklet to the coupon portion of the tag.

3. A combination booklet tag comprising a tag having a tag portion and a detachable coupon portion at one end of the tag portion, a fastening wire secured at the other end of the tag portion of the tag and extending along the tag toward the coupon portion thereof, said coupon portion of the tag being folded back over a part of the tag portion of the tag, a booklet overlying the coupon portion of the tag and at least a part of the tag portion of the tag, and means for removably anchoring the fastening wire in place along the tag and for securing the booklet to the coupon portion of the tag, said fastening wire overlying said folded over coupon portion of the tag to removably hold the same together with the booklet carried thereby upon the tag portion of the tag.

4. A combination booklet tag comprising a tag having a tag portion and a detachable coupon portion at one end of the tag portion, a fastening wire secured at the other end of the tag portion of the tag and extending along the tag toward the coupon portion thereof, a booklet overlying the coupon portion of the tag and at least a part of the tag portion of the tag, and securing means for securing the booklet to the coupon portion of the tag, said tag having an opening therein through which the fastening wire extends for removably anchoring the fastening wire in place along the tag.

5. A combination booklet tag comprising a tag having a tag portion and a detachable coupon portion at one end of the tag portion, a fastening wire secured at the other end of the tag portion of the tag and extending along the tag toward the coupon portion thereof, a booklet overlying the coupon portion of the tag and at least a part of the tag portion of the tag, and securing means for securing

60
65

the booklet to the coupon portion of the tag, said tag having an opening therein at the juncture of the tag portion and coupon portion of the tag through which the fastening wire extends for removably anchoring the fastening wire in place along the tag.

6. A combination booklet tag comprising a tag having a tag portion and a detachable coupon portion at one end of the tag portion, a fastening wire secured at the other end of the tag portion of the tag and extending along the tag toward the coupon portion thereof, said coupon portion of the tag being folded back over a part of the tag portion of the tag, a booklet overlying the coupon portion of the tag and at least a part of the tag portion of the tag, and securing means for securing the booklet to the coupon portion of the tag, said tag having an opening therein through which the fastening wire extends for removably anchoring the fastening wire in place along the tag.

7. A combination booklet tag comprising a tag having a tag portion and a detachable coupon portion at one end of the tag portion, a fastening wire secured at the other end of the tag portion of the tag and extending along the tag toward the coupon portion thereof, said coupon portion of the tag being folded back over a part of the tag portion of the tag, a booklet overlying the coupon portion of the tag and at least a part of the tag portion of the tag, and securing means for securing the booklet to the coupon portion of the tag, said tag having an opening therein at the juncture of the tag portion and coupon portion of the tag through which the fastening wire extends for removably anchoring the fastening wire in place along the tag.

8. A combination booklet tag comprising a tag having a tag portion and a detachable coupon portion at one end of the tag portion, a fastening wire secured at the other end of the tag portion of the tag and extending along the tag toward the coupon portion thereof, said coupon portion of the tag extending beyond said one end of the tag portion of the tag, a booklet overlying the coupon portion of the tag and at least a part of the tag portion of the tag, tab means formed in the tag portion adjacent said other end thereof and removably receiving the booklet, and means for removably anchoring the fastening wire in place along the tag and for securing the booklet to the coupon portion of the tag.

9. A combination booklet tag comprising a tag, a fastening wire secured at one end of the tag and extending along the tag toward the other end thereof, a booklet overlying at least a part of the tag, and means for removably anchoring the fastening wire in place along the tag and for securing the booklet to the tag.

10. A combination booklet tag comprising a tag, a fastening wire secured at one end of the tag and extending along the tag toward the other end thereof, a booklet overlying at least a part of the tag, and securing means for securing the booklet to the tag, said tag having an opening therein through which the fastening wire extends for removably anchoring the fastening wire in place along the tag.
